United States Patent Office.

ISRAEL FOSTER, OF PHILADELPHIA, PENNSYLVANIA.

Design No. 4,032, dated May 17, 1870.

DESIGN FOR A CARPET-PATTERN.

The Schedule referred to in these Letters Patent and making part of the same.

I, ISRAEL FOSTER, of Philadelphia, county of Philadelphia, State of Pennsylvania, have invented or produced a Design for a Carpet-Pattern, of which the following is a specification.

The accompanying photograph fully represents my design, the remainder of the pattern being merely a repetition of that which is shown.

The design consists in the arrangement, upon any suitable ground-work, of four figures, A, A', B, and B', surrounding a central figure, C, the latter consisting of a branch, leaves, and bunch of fruit, arranged substantially as shown.

The figure A is composed of a central ornament, A, representing a bunch of fruit, of two concentric circles, b and c, with intervening scallops d, and of an outer wreath, e, consisting of flowers, leaves, and stems, suitably arranged.

The figure A' closely resembles the figure A, the main point of difference being that the scallops e are outside of instead of between the circles.

The figure B is eight pointed, it having a border composed of curved ribs f, outside of which is a lace-like edging, h.

The interior of the figure is made up of a central ornament, i, dotted ground-work k, curved angular rib l, and scallops m, surrounding the latter.

The interior of the figure B' is composed of concentric circles, surrounded by a border and edging similar to that of the figure B.

Irrespective of the colors employed,

I claim the design for a carpet-pattern, substantially as described, and as represented in and by the accompanying drawing.

In testimony whereof I have signed my name to this specification in the presence of two subscribing witnesses.

ISRAEL FOSTER.
